UNITED STATES PATENT OFFICE.

JACOB J. SMITH, OF CHICAGO, ILLINOIS.

OIL-GAS GENERATOR AND BURNER.

1,326,469.

Specification of Letters Patent. Patented Dec. 30, 1919.

Application filed July 15, 1918. Serial No. 245,029.

To all whom it may concern:

Be it known that I, JACOB J. SMITH, a citizen of the United States, and a resident of the city of Chicago, in the county of Cook 5 and State of Illinois, have invented certain new and useful Improvements in Oil-Gas Generators and Burners; and I do hereby declare that the following is a full, clear, and exact description of the same, reference 10 being had to the accompanying drawings, and to the numerals of reference marked thereon, which form a part of this specification.

This invention pertains to an improved 15 type of an oil-gas generator and burner wherein the oil supply pipe is inclined downwardly toward its entrance end to permit the same to drain toward the supply and prevent impurities or carbon from entering 20 the carbureting parts of the device. The inclined supply pipe also serves as an oil vaporizing means which is first heated by a starting burner and afterward by a generating burner to generate an oil vapor adapted 25 to be carbureted with air to form an oil-gas. The generated oil-gas is admitted into a storage tank to be used as a fuel in said generating burner to perpetuate the process of oil-gas generation and is furthermore used 30 as a fuel to burn in cooking burners which are integrally formed on said storage tank.

It is an object of this invention to construct an oil-gas generator having an oil supply and generating pipe inclined toward 35 the inlet end to prevent carbonization of the generator parts.

Another object of the invention is the construction of an oil-gas generator and burner wherein the cooking burners are integrally formed on the oil-gas storage tank. 40

It is also an object of the invention to provide an oil-gas generator and burner having an inclined oil supply and generating pipe adapted to be initially heated by a 45 wick starting burner provided with an under feed.

It is a further object of this invention to construct an oil-gas generator and burner wherein oil is heated and vaporized and 50 then carbureted with air to form an oil-gas fuel adapted for use in cooking burners and in a generating burner for the purpose of continuing the process of oil-gas generation.

It is an important object of the invention 55 to provide a generating burner of simple

construction wherein kerosene oil is first volatilized by a starting or a generating burner and is then admitted into a carbureter to permit air to be carbureted therewith to form an oil-gas. 60

Other and further important objects of this invention will be apparent from the disclosures in the specification and drawings.

The invention (in a preferred form) is illustrated in the drawings and hereinafter 65 more fully described.

On the drawings:

Figure 1 is a top plan view of an oil-gas generator and burner embodying the principles of this invention. 70

Fig. 2 is a front elevation thereof.

Fig. 3 is a section taken on line 3—3, of Fig. 1.

Fig. 4 is an end view of the device.

Fig. 5 is a section taken on line 5—5, of Fig. 1. 75

Fig. 6 is an enlarged detail section taken on line 6—6, of Fig. 2, with the carbureting pipe shown entirely in section.

Fig. 7 is an enlarged fragmentary detail section taken on line 7—7, of Fig. 2, with parts omitted and with parts shown in elevation. 80

Fig. 8 is an enlarged front end view of the valve. 85

Fig. 9 is a front elevation of the generating burner removed from the device.

Fig. 10 is a fragmentary detail section taken on line 10—10, of Fig. 7.

As shown on the drawings:

The reference numeral 1, indicates a large casing, gas reservoir or gas storage tank, provided with an aperture or opening 2, in the front wall thereof, surrounded by an outwardly projecting collar 3. Integrally formed on the top of each end of the casing 1, is a cooking burner comprising a burner box 4, having a plurality of burner or gas openings or apertures 5, formed in the top wall or plate thereof. The upper corners of each of the burner boxes 4, are notched, as denoted by the reference numeral 6, to permit baffle plates to be mounted upon the burner boxes if desired. Integrally formed on the bottom and at one end of the casing 100 1, and in communication with the interior thereof, is smaller or auxiliary gas casing 7, provided with an inlet opening 8, in the outer end wall thereof, for a purpose hereinafter described. Formed within the cas- 105 110

ing 1, and separating the interior thereof from the interior of the auxiliary casing 7, is a partition or wall 9, constructed to leave an opening 10, to permit gas from the auxiliary casing to pass upwardly into the main or upper casing 1.

Rigidly secured to the back of the casing 1, are the upper ends of angle supports or legs 11, the horizontal positions of which 10 serve as feet. Disposed longitudinally in front of the auxiliary casing 7, and extending beyond the ends thereof is a fuel mixing or carbureting pipe 12, one end of which is curved to form an elbow 13, having 15 integrally formed on the inturned end thereof of a flange rim or ring 14, which is rigidly secured to the outer end wall of the auxiliary casing 7, to register with the inlet opening 8.

Secured or projecting into the collar 3, of 20 the main gas casing 1, is one end of a stub pipe or neck 15, on the outer end of which is integrally formed or rigidly secured a generating burner disposed in front of the 25 casing 1, and comprising a main pipe 16, of squared or angular cross-section and inclined with respect to the horizontal. The outer end portion of the pipe 16, is turned vertically downwardly to form a branch 30 pipe 17. Both ends of the generating burner are closed, and the front surface or wall of said generating burner is provided with a plurality of burner apertures or openings 18. The front wall of the branch pipe 17, 35 is also provided with a plurality of apertures or openings 19, disposed transversely across said branch pipe near the lower end thereof. Formed at the bent portion or at the elbow of the generating burner is a projection 20, on the end of which is secured a supporting or retaining latch 21,

The projecting finger or free end of the latch 21, engages and supports the downwardly projecting discharge arm 22, integrally formed on the higher end of a long 45 oil supply or oil-gas generating pipe or tube 23, which is disposed directly in front of the generating burner and is inclined downwardly toward the inlet end 24, thereof. 50 The inlet arm 24, is directed downwardly and is connected by means of a feed or supply pipe 25, with a kerosene or oil supply tank, not shown. Secured to the inner end of the generating burner 16, is a bracket or 55 arm 26, which engages underneath the inclined generating pipe 23, to help support the same in position.

The discharge arm 22, is disposed in front 60 of the branch generating burner pipe 17, and together therewith project into a box or shield 27, open at the top and at the outer end, and attached to the rear of the generating burner by screws or bolts 28. The shield 27, is positioned adjacent the open 65 lower end of the carbureting pipe 12, and

the end wall of said shield is provided with an opening disposed directly opposite the open end of said carbureting pipe.

Associated with the lower end of the discharge arm 22, and projecting longitudinally through the shield 27, is a needle valve mechanism for controlling the flow of heated vaporized oil from the generating pipe 23, into the carbureting pipe 12. The valve mechanism embraces a short pipe or tube 29, 70 integrally formed at right angles to the lower portion of the discharge arm 22, or projecting therethrough, with the internally threaded passage 30, thereof communicating with the passage 31, of said discharge arm. 75 The outer and inner ends of said valve tube 29, are externally threaded. Adjustably threaded within the passage 30, is a threaded shank or screw portion 32, having integrally formed on one end thereof an actuating rod 33, which projects outwardly through an apertured cap 34, removably threaded upon the externally threaded outer end of the valve tube 29. Disposed within the cap 34, is a packing 35, and a washer 36, 80 adapted to afford a tight joint around the valve rod 33. The outer end of the valve rod 33, is squared as denoted by the reference numeral 37, to permit a wrench or other suitable tool to be applied thereto to rotate 85 the valve rod. Integrally formed on the other end of the threaded shank 32, is a valve stem 38, of reduced diameter, which projects longitudinally through the passage 30, and has the outer or projecting end thereof of reduced and chamfered on one side only as denoted by the reference numeral 39, to 90 form a needle valve point 40. The chamfered needle valve point 40, adjustably projects through an outlet opening formed centrally in a nut cap 41, which is removably threaded on the inner end of the valve tube 29, and has a cylindrical portion 42, thereof projecting through the opening provided 95 for the purpose in the end wall of the shield 27. The valve needle 40, is chamfered or beveled to afford a means for regulating the valve outlet, by rotation of the valve rod 33.

To start the process of oil-gas generation 100 a starting burner is positioned below the generating pipe 23. The starting burner comprises an open trough 43, supported at one end by a bracket 44, attached to the bottom of the generating burner 16. The other end of the trough 43, is attached to the bracket 105 arm 26. A wick 45, is placed longitudinally within the open trough 43, and is saturated with kerosene or any other suitable oil from below by means of an under feed neck or sleeve 46, which projects outwardly from the 110 central front portion of the trough. The outer open end of the under feed sleeve 46, is removably plugged or closed by a screw 47, to permit cleaning of the passage leading 115 into the trough. A vertical priming or feed 120

pipe 48, is threaded into an opening provided in the top of the sleeve 46, to permit small quantities of kerosene oil to be poured therein. The oil entering the pipe 48, of course flows through the passage in the sleeve 46, and into the lower portion of the trough to saturate the wick 45, from below.

The operation is as follows:

To start the process of oil-gas generation 10 kerosene oil or alcohol is poured into the priming pipe 48, and flows through the sleeve 46, into the trough 43, of the starting burner to saturate the wick 45. The saturated wick is lighted and the heat resulting 15 from the burning wick acts to rapidly heat the generating pipe 23, disposed above the starting burner. Kerosene or any other suitable hydro-carbon fuel is supplied to the inclined generating pipe 23, through the 20 main supply pipe 25, and the intake arm 24. As clearly shown the generating or vaporizing pipe 23, is inclined downwardly toward its inlet end, thereby preventing any impurities, foreign matter or carbon contained 25 in the oil from entering the device. As the intake arm 24, fills with kerosene small quantities thereof gradually flow into the heated pipe 23, the heat from the starting burner acting to vaporize the oil to form a 30 gas which passes through the generating pipe 23, and the discharge arm 22, into the passage 30, of the valve mechanism. The valve rod 33, is rotated to retract or draw the valve stem 38, inwardly, thereby causing 35 the chamfered valve needle 40, to also move inwardly to open the valve outlet in the cap end 42, permitting the vaporized oil to pass outwardly.

The draft caused by the air flowing into 40 the carbureting tube 12, and upwardly through the casings 7 and 1, acts to draw the escaping vaporized oil from the valve mechanism into the carbureting tube. The air in the tube 12, is thus carbureted with 45 the vaporized oil to form an oil-gas, which, of course, flows through the opening 8, into the auxiliary casing 7, and upwardly through the opening 10, into the casing 1. The oil-gas from the casing 1, is permitted 50 to escape through the cooking burner apertures 5. The escaping oil-gas is lighted and furnishes a very hot flame suitable for cooking purposes. Some of the generated oil-gas from the casing 1, flows through the 55 opening 2, into the generating burner 16-17, and out through the apertures 18 and 19. The escaping oil-gas from the generating burner is lighted and the resulting flames engage the generating pipe 23 and 60 the discharge arm 22, thereof, as well as the valve mechanism disposed within the shield 27, which acts to direct the flames from the burner apertures 19, around the valve tube 29, to heat the valve parts to prevent the 65 vaporized oil therein from cooling before it is

mixed with air in the carbureting tube 12. The process of oil-gas generation is thus continued, after once being started by the starting burner, which of course goes out after the kerosene with which the wick 45, 70 is saturated has burned up.

When it is desired to shut off the burner the supply of oil from the tube 25, is closed by any suitable valve positioned in the main feed pipe. The cooking burners and the 75 generating burner are then allowed to burn until all of the oil-gas fuel in the casings 7 and 1, as used up.

The inclined position of the generating pipe 23, acts to prevent carbonization of the 80 various parts of the generator and burner, and further permits any impurities which may have collected in the lower portion of the intake arm 24, to be drawn off by removing the closure nut 49, which connects 85 the tubes 25, to the arm 24. The under feed arrangement of the starting burner permits additional quantities of priming oil to be poured into the pipe 48, while the wick 45, is burning, in case the device does not get 90 properly started by a single saturation of the wick. The pouring of oil on top of the wick 45, when the same is burning of course is very dangerous, and the under feed arrangement affords a safe means for properly 95 starting the process of oil-gas generation.

The removal of the valve caps 34 and 41, permits proper cleaning of the valve mechanism. The sleeve 46, of the starting burner may also be cleaned by removing the 100 screw 47.

I am aware that numerous details of construction may be varied through a wide range without departing from the principles of this invention, and I therefore 105 do not purpose limiting the patent granted otherwise than necessitated by the prior art.

I claim as my invention:

1. An oil-gas generator and burner comprising an oil-gas storage casing, cooking 110 burners integrally formed thereon, a generating burner mounted on the front of said casing, a starting burner supported thereon, an oil supply generating pipe disposed in front of said generating burner and above 115 said starting burner, said supply and generating pipe inclined downwardly toward the oil intake end thereof, a valve mechanism formed on the discharge end of said supply and generating pipe for controlling 120 the flow of vaporized oil, and a carbureting tube having one end connected with said casing and the other open and disposed adjacent the valve mechanism to receive vaporized oil therefrom to carburet air there- 125 with to form an oil-gas.

2. An oil-gas generator and burner embracing a gas tank, a generating pipe disposed to the front thereof and inclined upwardly toward the discharge end thereof, 130

means for initially heating the same to vaporize the oil therein, carbureting means connected with said tank for receiving the vaporized oil and carbureting air therewith to form an oil-gas for storage in said tank, and an inclined generating burner supporting the discharge end of the generating pipe and connected with said tank to receive oil-gas therefrom and burn the same to heat said inclined generating pipe to continue the process of oil-gas generation.

3. In an oil-gas generator and burner of the class described, an inclined generating pipe having an intake and a discharge end, starting means for initially heating the generating pipe to vaporize the oil therein, inclined means for continuing the process of vaporization, a valve mechanism formed on the discharge end of said generating pipe to control the flow of vaporized oil therefrom, an apertured arm forming a part of said inclined means and adapted to heat said valve mechanism, carbureting means for receiving the vaporized oil and mixing the same with air to form an oil-gas fuel, a casing connected with said carbureting means and with said means for continuing the process of oil vaporization adapted to hold the oil-gas fuel, and cooking burners formed on the top of said casing adapted to burn the oil-gas fuel.

4. In a burner of the class described, storage means, an inclined generating pipe in the front thereof, an intake arm integrally formed at one end of said generating pipe, a discharge arm integrally formed at the other end of said generating pipe, a starting burner disposed below said generating pipe to initially heat the same to vaporize the oil therein, a valve mechanism formed on the lower end of the discharge arm for controlling the passage of vaporized oil therefrom, an air intake mixing pipe connected with said storage means and having an open end thereof disposed opposite said valve mechanism to receive vaporized oil therefrom and mix the same with air to form an oil-gas adapted to be held in said storage means, an inclined generating burner connected with said storage means, an arm formed thereon and disposed behind said discharge arm and said valve mechanism, said generating burner and arm having openings therein to burn the oil-gas from said storage means to continue the process of oil-gas generation, and a shield disposed around said valve mechanism, said discharge arm and said generating burner arm adapted to confine the flames from said generating arm openings around the discharge arm and valve mechanism to keep the vaporized oil heated until mixed with air.

5. In an oil-gas generator and burner of the class described, a storage tank having burner openings therein, and inclined generating burner connected with said tank, an inclined generating pipe, a starting burner supported below said generating pipe to initially heat the same to vaporize the oil therein, means forming a part of said starting burner for supplying the same with oil from below, a valve connected with said generating pipe for controlling the passage of vaporized oil therefrom, means forming a part of said generating burner for heating the valve, and a mixing pipe connected with said tank adapted to receive the vaporized oil from the valve and carburet air therewith to form an oil-gas adapted to be burned as a fuel in said tank burner openings and by said generating burner to continue the process of oil-gas generation.

6. A generating burner comprising storage means, a generating means inclined downwardly toward the intake end thereof, a starting burner trough disposed below said generating means, a wick therein, a sleeve connected with said trough, a feed pipe connected therewith to supply oil to said wick from below, said wick when saturated adapted to be lighted to initially heat the generating means to vaporize the oil therein, and mixing means adapted to carburet air with said vaporized oil to form an oil-gas for storage in said storage means until used.

7. An oil-gas generator and burner of the class described comprising a casing, a generating burner connected therewith, an inclined generating pipe disposed adjacent thereto, an under feed starting burner below said inclined generating pipe to initially heat the same to vaporize the oil therein, an adjustable valve mechanism formed on said generating pipe to control the flow of vaporized oil therefrom, mixing means connected with said casing adapted to receive the vaporized oil to mix air therewith to form an oil-gas adapted to be stored in said casing, a shield for said valve mechanism, and cooking burners formed on said casing adapted to burn the oil-gas for cooking purposes, said generating burner adapted to also burn the oil-gas to heat the generating pipe and valve mechanism to continue the process of oil-gas generating after the under feed starting burner goes out.

In testimony whereof I have hereunto subscribed my name in the presence of two subscribing witnesses.

JACOB J. SMITH.
